UNITED STATES PATENT OFFICE.

GUSTAV BOESCH, OF DANBURY, CONNECTICUT.

APPARATUS FOR APPLYING TIRES TO VEHICLE-WHEELS.

1,312,608.

Specification of Letters Patent.

Patented Aug. 12, 1919.

Application filed April 21, 1917. Serial No 163,572.

To all whom it may concern:

Be it known that I, GUSTAV BOESCH, a citizen of the United States, and a resident of Danbury, in the county of Fairfield and 5 State of Connecticut, have invented an Improvement in Apparatus for Applying Tires to Vehicle-Wheels, of which the following is a specification.

This invention relates to apparatus for 10 applying rubber tires and the like to vehicle wheels.

Certain of the objects thereof are to provide several features in apparatus of the above type of simple and practical construction and efficient action. Another object is to provide apparatus of the above type well suited for rapid and convenient use. Another object is to provide apparatus of the above type in which the parts are durable 15 and compact and yet the entire device is of inexpensive construction. Other objects will be in part obvious and in part pointed out hereinafter.

The invention accordingly consists in the 20 features of construction, combinations of elements and arrangement of parts which will be exemplified in the structure herein-after described and the scope of the application of which will be indicated in the following claims.

In the accompanying drawings in which is shown one of various possible embodiments of this invention,

Figure 1 is a front elevation showing the 35 apparatus mounted upon a bench.

Fig. 2 is a sectional view taken along the line A—A of Fig. 1.

Fig. 3 is a sectional view along the line B—B of Fig. 1, the view being taken in an 40 upward direction and certain parts being removed to show the construction more clearly.

Fig. 4 is a side elevation of the apparatus of Fig. 1, the parts being shown at another 45 stage of their action.

Fig. 5 is a top plan view of a portion of the apparatus shown in Fig. 4.

Similar reference characters refer to similar parts throughout the several views of 50 the drawings.

Referring now to Fig. 1 of the drawings, there is shown a supporting frame comprising the arms 1 and 2 detachably interlocking with the pairs of posts 3—3 and 4—4, the 55 latter being best shown in Figs. 4 and 5 of the drawings. These posts are preferably

formed integral with a base member 5 which is secured as by the screws 6 to a work bench 7.

The arms 1 and 2 join at 8 and 9 respectively an upright guide 10, these several parts 1, 2 and 10 preferably being integral.

Slidably fitted upon the guide 10 which is preferably rectangular in cross section, is a sleeve 11, and the latter is provided with a 60 projection 12, recessed at 13 and having fitted therein the plunger 14, normally urged outwardly by the spring 15 into engagement with the surface of the guide. By this arrangement, the sleeve 11 may be moved 65 along the guide 10 to any desired point and yet will be held in the position into which it is moved by the gripping action of the plunger 14. Rigidly mounted upon the sleeve 11 and extending outwardly therefrom, is a supporting pin 16 adapted to enter and support the hub of a wheel indicated in dotted lines at 17 in Fig. 1 of the drawings. By this means a wheel, and it is to be understood that this apparatus is more 70 especially adapted for small wheels such as those of children's carriages, may be quickly mounted in such manner as to permit its rotation, and may also be readily moved lengthwise of the guide 10 into the exact 75 position for the operations hereinafter described.

Formed upon the upper end of the guide or central frame member 10 is a post 18 which has removably secured, as by the 80 screws 19, to its upper surface an abutment device comprising the web 20 and the arms 21 and 22. Each of these arms terminates in an abutment, the lower surface of which is curved as at 23 to rest within the concave 85 rim of a vehicle wheel, and the outer edge of which is provided with an open recess 24. Journalled at the end of the arm 1 is a spindle 25 and similarly journalled at the end of arm 2 is a spindle 26, these spindles 100 being provided with the crank portions 27 to permit them to be rotated within their bearings 28. Secured to each spindle is a crown tooth ratchet 29 which co-acts with a pawl 30 pivotally mounted upon the arm in 105 proper position for such action.

The post 18 is provided with a horizontal recess 31 within which there is slidably fitted a lug 32 having formed thereon the side wings 33. Pivotally mounted between these 110 wings 33 as by means of the pin 34, are a pair of swinging jaws 35, for a purpose

hereinafter described. It may be noted that this feature is not shown in full lines in Fig. 1 of the drawings in order to avoid encumbering the disclosure, and it is to be noted 5 that this device is removable if necessary to prevent interference with wheels of certain shapes while the tire wires are being connected thereon.

Considering now the method of use and 10 action of the above apparatus, and referring first to Fig. 1 of the drawings, the wheel 36 is first mounted upon the pin 16 with its hub as indicated at 17; and unless the apparatus has been previously adjusted, the sleeve 11 15 is moved upwardly to bring the concave upper surface of the rim 37 against the lower curved surfaces 23 of the abutments 21 and 22. The action of the plunger 14 firmly holds the wheel in this position while the 20 tire 38 is wrapped about the rim 37 with the ends of its rubber portion resting against the outer surfaces of the abutments, the free ends 39 and 40 of this wire being passed through the grooves 24 and secured within 25 the slots 41 of the spindles 25 and 26 respectively. Cranks 27 are then rotated in the directions indicated by the arrows 42 and the free ends of the wire are coiled upon spindles 25 and 26; but it is to be noted that 30 this coiling action which is lengthwise of the spindle does not tend to cause the wires to ride out of the slots 24 or to pull the ends of the tire out of their proper aligned position in the rim 37. When the wires have 35 been sufficiently tightened, they are merely twisted together at their intersection, as indicated at 43 in Fig. 3 of the drawings, thus making a secure joint. The tire is now in condition to close the gap in the rubber 40 at the point where the joint in the wire is positioned and it is to be understood that the rubber is of sufficient length in its free normal condition to extend entirely about the circumference of the wheel. The ends 45 of the rubber tire have been held by the abutments 21 and 22 as the ends of the wire are drawn out and connected as above described. To close the joint, the sleeve 11 is merely moved downwardly a suitable dis- 50 tance on the guide 10 to bring the rubber between the tips of the jaws 35. These jaws are thereupon gripped about the rubber, being pressed toward one another by hand, and the wheel is at the same time turned by 55 hand on the spindle 16 as indicated by the arrows 44 to bring the tire end 45 over the joint. In a similar manner, the end 46 is worked over the joint by seizing the rubber at a point remote from the joint with 60 the jaws 35 and turning the wheel to slide the rubber into its proper position. It will be understood that it is necessary forcibly to work the ends of the rubber tire as above described over the joint in a wire on account 65 of the enlarged cross section of this joint and

the pressure of the wire against the tire. When, however, the ends of the tire are forced together, they will retain such position as the rubber is held not only frictionally but by reason of its being in its 70 normal state and free from compression or tension. The installation of the tire on the wheel is then complete and this cycle of operations may be repeated with other wheels.

It will thus be seen that there is provided apparatus in which the several objects of this invention are achieved. The ready adjustability of the parts conduces to their 75 rapid and convenient manipulation and their separable interlocking construction permits them to be readily assembled or taken apart. It will also be seen that the action of the apparatus is accurate and reliable and well suited for the hardest conditions of practical use.

As various possible embodiments might be made of the above invention and as various changes might be made in the embodiment above described, it is to be understood that all matter herein set forth or shown in the accompanying drawings is to be interpreted as illustrative and not in a limiting sense.

I claim as my invention:

1. In a tire applying apparatus, wheel supporting means, a vertical guide carrying said means and having a pair of upwardly extending arms, a horizontal post extending outwardly from the guide and disposed between said arms, an abutment device carried by said post and including a pair of spaced arms having horizontal wire receiving recesses in their outer ends and depending portions adapted to conformably fit in the tire-receiving groove of the wheel and a pair of vertically arranged turnable spindles carried by the respective arms of the guide and formed to engage the wire and to draw same taut and in opposite directions upon turning of the spindles, said spindles being disposed to the rear of the wire receiving recesses and having vertical downwardly extending slots to receive the wires.

2. In a tire applying apparatus, wheel supporting means, a pair of spaced tire abutment means formed to guidingly engage the wheel periphery and having horizontal outwardly facing wire-receiving grooves open at their outer ends, and a pair of vertical arranged wire tightening means arranged respectively on opposite sides of and to the rear of the wire-receiving grooves whereby during tightening of the wires the latter will be drawn toward and against the rear walls of the grooves to prevent disengagement of the wires from said grooves.

3. In a tire applying apparatus, wheel supporting means, a pair of spaced tire abutment means formed to guidingly en-

- gage the wheel periphery and having horizontal outwardly facing wire-receiving grooves open at their outer ends, and a pair of vertically arranged wire tightening means arranged respectively on opposite sides of and to the rear of the wire-receiving grooves whereby during tightening of the wires the latter will be drawn toward and against the rear walls of the grooves 5 to prevent disengagement of the wires from said grooves, said wire tightening means having downwardly facing wire receiving slots whereby to allow the wires to be placed in the grooves and slots in a single operation and movement.
4. In a tire applying apparatus, a wheel support, tire holding means associated with the support, wire tightening means coöperatively related to said tire holding means, 10 tire gripping means carried by the support and located in depending relation to the holding and tightening means so as to be overlapped by the wheel during the wire tightening operation, and means to allow 15 of adjustment of the wheel support so as to enable the wheel to be successively moved from the holding and tightening means to the gripping means.
5. In a tire applying apparatus, a base 20 having a spaced pair of spaced upwardly extending posts, a guide receivable in the space between the pair of posts and having a depending relation to the base, said guide having a pair of upwardly extending arms 25 receivable in the spaces between the posts of the respective pair of posts, a horizontal recessed post extending outwardly from the guide, a slide fitted in the recess of said horizontal post, an abutment device for the 30 tire ends carried by the slide, and wire tightening means borne by the arms.
6. In a tire applying apparatus, a base 35 formed to seat on the top of a work bench or the like and having a guide extending downwardly over the front of the bench, 40 means borne by the guide to support a wheel, abutment means borne by the guide to engage the ends of the tire, said abutment means having wire engaging parts, means borne by the base to tighten the ends 45 of the wire, means borne by the guide and located below the abutment and wire tightening means to grip the tire ends, and means to allow of adjustment of said wheel supporting means on the guide whereby to 50 allow the wheel to be successively moved from a position enabling operation of the tightening means to a position enabling operation of the tire end gripping means.
7. In a tire applying apparatus, a base 55 having a spaced pair of spaced upwardly extending posts, a guide receivable in the space between the pair of posts and having a depending relation to the base, said guide having a pair of upwardly extending arms 60 receivable in the spaces between the posts of the respective pair of posts, said base being formed for securement to a work bench or the like and said posts supporting the guide removably and in front of the 65 bench, wire tightening means borne by the arms, and a wheel support borne by the guide.
- In testimony whereof, I have signed my name to this specification this 11th day of 70 April 1917.
- 75

GUSTAV BOESCH.
